UNITED STATES PATENT OFFICE.

LOUIS F. HART, OF CLEVELAND, OHIO, ASSIGNOR TO THE HART MANUFACTURING COMPANY, OF CLEVELAND, OHIO, A CORPORATION OF OHIO.

DIESTOCK.

Application filed August 27, 1921. Serial No. 495,981.

To all whom it may concern:

Be it known that I, LOUIS F. HART, a citizen of the United States, and a resident of Cleveland, county of Cuyahoga, and 5 State of Ohio, have invented a new and useful Improvement in Diestocks, of which the following is a specification, the principle of the invention being herein explained and the best mode in which I have contemplated applying 10 that principle, so as to distinguish it from other inventions.

The present improved die stock is of the same general type as described and claimed in U. S. Letters Patent No. 1,146,871, issued 15 to me under date of July 20, 1915. Changes in construction, however, have been made with the object of rendering such die stocks more adaptable for use in cutting threads on bolts, such threads not requiring to be 20 tapered. With this end in view, among other things, I have devised detachable centering means which permit the die stock to be operated close up to the head of the bolt or a shoulder thereon. I have also incorporated 25 in the die stock proper means whereby the accurate setting of the individual dies or chasers is insured.

To the accomplishment of the foregoing and related ends, the invention, then, consists 30 of the means hereinafter fully described and particularly pointed out in the claims.

The annexed drawings and the following description set forth in detail certain mechanism embodying the invention, such disclosed means constituting, however, but several of the various mechanical forms in which the principle of the invention may be used.

40 In said annexed drawings:

Fig. 1 is a rear elevation of my improved die stock showing the work centering device or chuck as attached; Fig. 2 is an elevational view of such centering device by 45 itself viewed from the opposite side to that shown in Fig. 1; Fig. 3 is an axial section of the die stock, the plane of the section being indicated by the line 3—3, Fig. 1; Fig. 4 is an axial section corresponding 50 with that of Fig. 3 but showing only the work centering device and this a modified form; Fig. 5 is a front elevational view of the die stock; Fig. 6 is a transverse section taken on the plane indicated by the line

6—6, Fig. 5; and Fig. 7 is partly a sectional view and partly an end elevation of certain of the elements appearing in Fig. 6.

The main body 1 of the die stock is in general of familiar form, being provided with sockets 2 for the reception of handles 3 60 as usual. Such body is also provided with a set of radial or substantially radial openings 4 (see Figs. 3, 5 and 6) that constitute guides for the chaser dies 5. Four such dies are shown but it will be understood that 65 the number may be varied in die stocks of a different size or for a different use than the particular one illustrated; also that should it be found desirable to employ the present construction of stock for use in 70 threading pipe or the like, the threads of such dies may be cut on a taper if desired. Said dies 5 are positioned radially in openings 4 by means of a cam plate 6 rotatably mounted on the body 1 and formed with a 75 series of cam grooves 7 that engage with pins 8 in the dies as will be readily understood. For the purpose of retaining said cam plate 8 in adjusted position a screw 10 is rotatably supported in the lugs 11 that 80 project upwardly from the die stock body 1. Threaded upon and oscillatory about said screw 10 is a catch 12 that is capable of transverse adjustment within the space between the two lugs 11 by rotating the screw 85 in one direction or the other, while at the same time said catch is oscillatory about the screw as an axis to engage and disengage a notch 13 in the cam plate. Further details of the construction of this portion of 90 the device will be found described in my aforesaid patent and need not be repeated here as they form no part of the present invention.

Where a straight thread is being cut in 95 place of a taper thread the matter of accuracy in size is of greater importance and I accordingly provide in connection with the chaser dies just described a device for insuring accuracy in setting. It is of course 100 extremely difficult as well as undesirable, on account of possible binding, to fit the pins 8 of the dies in the respective cam grooves 7 so that there will be no lost motion and furthermore, with use, the grooves 105 will tend to wear. For the purpose of setting, one of the dies is provided with one or more transverse marks 5^a and it will

be obvious that if the pin of this die has some play in its groove, it may move from its set position a trifle when the cutting operation is begun. As shown in Figs. 5, 6 and 7, I avoid this difficulty by providing a spring 14 that engages with the marked die so as to likewise retain it with its pin 8 in contact with the outer wall of the corresponding groove 7. While this spring may take on various forms, that shown in the figures in question has been designed with a view to occupying a minimum space while yet being adequate for the purpose, such spring consisting of a piece of tempered wire bent at one end to form an eye 14^a adapted for the reception of a set screw 15 whereby the spring is secured to the adjacent portion of the body 1. The body of the spring adjacent such eye lies at right angles thereto and projects through a small opening 16 (which prevents the spring from rotating about the set screws) alongside the die in question and has its outer end 14^b bent at right angles to the body so as to engage a notch 17 in such die. The spring, it will accordingly be observed, acts as a torsion spring to hold the pin 8 at all times against the outer wall of the groove 7, as clearly shown in Fig. 6. The adjustment of the cam plate to bring this die into properly set position, as indicated by the mark 5^a thereon, will of course at the same time set the other dies correctly.

As previously indicated, I provide a detachable centering device, this consisting of an annulus or ring 20 having approximately the same internal diameter as the body 1 and adapted to fit against the rear of the latter, being secured in place by means of two capstan headed screws 21 that pass through openings in laterally projecting ears 22 on such annulus 20 into registering openings in the sockets 2 of the main body 1 of the die stock. The annulus or ring 20 is provided with a plurality of centering pins or jaws 23, three being shown, such jaws being held in radial or approximately radial slots 24 formed in the inner face of the ring. The jaws 23 are preferably of rectangular cross section and for convenience in manufacture the slots 24 are milled or otherwise cut through the inner wall of the ring and in order to cover over the portions of such slots that would otherwise be exposed, a short section 25 of light gauge tubing is fitted to the interior of the annulus 20 forwardly of the jaws 23. It is sufficient for the purpose if such tubular section 25 be simply pressed or sprung into the opening in the annulus or ring as there is no strain imposed thereon tending to dislocate same.

For the purpose of radially positioning the jaws 23, a cam plate 26 as usual is pro-

vided, such plate being rotatably mounted upon the annulus or ring 20 and having a series of cam grooves 27 that engage with pins 28 on the respective jaws. A small set screw 29 serves to prevent the cam plate 70 from slipping off the ring when the latter is detached from the main body of the die stock, while in the attached condition of the centering device the cam plate, as clearly shown in Fig. 3, is securely held between 75 such main body and the annulus or ring. Rotation of the cam plate may of course be effected in any suitable way, the means shown consisting of a screw 30 rotatably held in lugs 31 projecting from the annulus 80 or ring 20 and engaging a series of teeth 32 on the cam plate forming a segmental gear.

The modification illustrated in Fig. 4 relates to the form of the centering blocks 35 which are here shown as circular or approximately circular in cross section. This permits of the use of circular openings 36 which may be drilled in the annular member 37 instead of the rectangular slots 24. There is accordingly no occasion to use in this 90 form the tube-section 25 to cover the exposed portions of such slots as in the first described construction.

The mode of operation of my improved die stock should be apparent from the foregoing description of its component parts and of their individual operation. It will be noted, however, that by means of the screws 21 the centering device may be instantly detached in its entirety from the 100 main body of the die stock so that the latter may be brought close up to the head of a bolt or a shoulder thereon. When on the contrary no such obstacle is present, it will be desirable to employ the centering device 105 and this as a unit is just as readily replaced. Finally the tension spring provided in conjunction with the marked die 5 which is used in setting the die stock to cut a thread of 110 desired size insures the accuracy of such setting at all times. The form of the recess or notch 17 in the side face of the die 5, and the manner in which the torsion spring 14 engages therewith, is such as to permit of the ready withdrawal of the die 115 when it is desired to change one set of such dies for another in cutting different sizes. The upper end of the spring, however, will immediately engage with the notch when the die is inserted.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character de-

scribed, the combination with a main body-member and dies adjustably held therein; of an annular member detachably secured to said body-member, radially adjustable 5 guide blocks in said annular member, and a cam-plate for positioning said blocks, said cam-plate being rotatably mounted on the face of said annular member designed to contact with said body-member so as to 10 be held between said two members.

2. In mechanism of the character described, the combination with a main body-member and dies adjustably held therein; of an annular member detachably secured 15 to said body-member, said annular member being formed with approximately radial slots cut in its inner face and intersecting the central opening therein, guide blocks movably held in such slots, a cam-plate for 20 positioning said blocks, and a tube-section

fitted within said annular member so as to cover the exposed portions of such slots.

3. In mechanism of the character described, the combination of a body-member; dies movable in said member, one of said 25 dies being marked for setting and having a notch in one of its sides; a cam-plate rotatably secured to one end of said member adapted to position said dies therein; and a torsion spring secured at one end to said 30 member and having its other end bent at an angle to engage the notch in said die so as to resiliently force the latter outwardly against the corresponding element on said plate, said spring also permitting the removal of said die without the displacement 35 of said bent end.

Signed by me this 23d day of August, 1921.

LOUIS F. HART.
